CHARLES M. ABERCROMBIE, OF BRIDGEPORT, CONNECTICUT, ASSIGNOR TO THE SINGER MANUFACTURING COMPANY, A CORPORATION OF NEW JERSEY.

CLOTH-PRESSER MECHANISM FOR SEWING-MACHINES.

1,150,321.

Specification of Letters Patent.

Patented Aug. 17, 1915.

Application filed March 12, 1912. Serial No. 683,384.

To all whom it may concern:

Be it known that I, CHARLES M. ABERCROMBIE, a citizen of the United States, residing at Bridgeport, in the county of Fairfield and State of Connecticut, have invented certain new and useful Improvements in Cloth-Presser Mechanism for Sewing-Machines, of which the following is a specification, reference being had therein to the accompanying drawings.

This invention relates to improvements in cloth-presser mechanism for sewing machines, and is designed particularly for use in connection with stitching hemstitch, embroidery and open-work seams, and has for its object to provide a cloth-presser adapted to the feeding of edge or hem folds presenting a greater number of plies of fabric at one side of the needle actuation than at the other.

In the construction of cloth-presser mechanisms such as are used in connection with the feeding of a comparatively large number of superposed plies of fabric unevenly distributed in the line of the seam it is all important, when such fabrics are of very thin texture as when hemstitching fine linens, that the control of the feeding mechanism shall be such as to prevent, as far as possible, the plies from slipping one upon the other or from crowding when being drawn beneath the presser-foot.

To effect the feeding operation previously referred to it is common to employ rocking cloth-pressers having cloth feeding surfaces of a length considerably greater than is employed in connection with ordinary stitching, which greatly increases the distance between the front or receiving ends of the cloth-pressers and the vertical axis of the spring-pressed presser-bar or bars, and when introducing several thicknesses of fabric under the receiving ends of the cloth-pressers the latter are rocked on their pivots, which, in the earlier constructions, effects vertical movements of the vertically mounted spring-pressed cloth-presser carriers and the greater the distance between the pivotal points of the cloth-pressers from a line corresponding to the vertical axis of the carriers the greater is the resistance offered to the feeding of the fabric under the receiving ends of the pressers.

In the present construction the presser-

carriers comprise spring-pressed levers pivotally connected to the lower end of the main spring-pressed cloth presser-bar, and when introducing the fabric beneath the receiving ends of the cloth-pressers the pressure of the latter on the fabric is comparatively light until after the fabric has passed under the presser-feet a distance sufficient to bring their effective surfaces in alinement with the plane of said fabric.

In the accompanying drawings illustrating the invention, in the several figures of which like parts are similarly designated, Figure 1 is a front end elevation of the bracket arm of a hemstitch sewing machine equipped with the present invention, together with a front edge view of the sewing machine bed-plate. Figs. 2 and 3 are front and rear side views, respectively, of the improved cloth-presser mechanism.

The invention is shown as applied to one form of Singer commercial hemstitch sewing machine, but as it relates only to the construction and application of the cloth-presser mechanism, only such reference will be made to the other elements of the machine as is deemed necessary for a proper understanding of its application.

Referring to the figures, 1 represents the usual bracket arm of the sewing machine mounted upon the bed-plate 2, 3 the presser-bar operatively mounted in the end of the overhanging arm and having the usual presser spring 4, 5 a presser-bar bracket secured by screw 6 to the lower end of said bar, 7 and 8 left and right hand presser-foot carrying levers mounted on the bracket 5 by pivot screw 9, the latter being held against accidental displacement by a screw 10, and 11 and 12 left and right hand presser-feet pivotally attached by pins, as 13, to their respective levers 7 and 8.

14 and 15 represent springs seated in suitable openings, as 16, formed in the bracket 5. The lower ends of said springs are seated on the upper edges of the respective levers 7 and 8, and their upper ends contact with the end walls, as 17, of the screws 18 and 19 threaded into the upper end of the bracket 5, the adjustment of said screws effecting an independent control of the amount of pressure exerted by each of the presser-feet, thus making it practical to give to the plies of fabric passing at one side of the

needle a greater or lesser degree of pressure than to the ply or plies passing at the opposite side of the needle.

20 represents the commonly employed presser-bar lifting lever for effecting vertical movements of said presser-bar in opposition to the resiliency of the spring 4.

From the foregoing it will be understood that when the fabric is presented to the receiving ends of the cloth-pressers it acts to rock the levers 7 in opposition to the springs 14 and 15 until the upper edge of said levers are brought near or in contact with the lower edge of the bracket 5, so it will be seen that in the earlier constructions the initial feeding of the fabric to the action of the needle forces the vertically mounted spring cloth-presser carriers upward by a leverage applied at a substantial distance from the axis of said carriers, while in the present construction a leverage is provided which effects an entrance of the fabric beneath the cloth-pressers under conditions of reduced pressure.

Copies of this patent may be obtained for five cents each, by addressing the "Commissioner of Patents, Washington, D. C."

sure while the maximum of pressure becomes effective as soon as the fabric has passed the 25 line of pivotal engagement of the cloth-pressers with their carriers.

Claim:—

In a cloth-presser mechanism for sewing machines, the combination with a spring depressed cloth-presser carrying bar, a bracket 30 carried by the latter and provided with spring pockets, spring controlled cloth-presser carrying levers pivoted at one end to said bracket and at their opposite ends 35 provided with pivotally secured cloth-pressers, of springs mounted in said pockets and acting independently on said levers to depress said cloth-pressers.

In testimony whereof, I have signed my 40 name to this specification, in the presence of two subscribing witnesses.

CHARLES M. ABERCROMBIE.
